SAFETY RAZOR

Howard Addison Johnston, Toronto, Ontario,
Canada

Application January 18, 1932, Serial No. 587,236

4 Claims. (Cl. 36—12)

This invention relates to safety razors and more particularly to that type in which the blade is flexed transversely between two clamping members and my object is to provide a razor of this type in which the parts thereof may be readily exposed for cleaning purposes without disconnecting them thereby facilitating the conditioning for use of the parts after they have been cleaned. Other objects I have in mind will hereinafter appear.

I attain my object by hinging a blade holder on the pintle of a hinge connection between the clamping members which comprise a base plate and a cover plate. One end of the blade is removably carried on the holder and the plates are recessed to provide clearance for the holder so that the plates will contact with the blade throughout its length. Means are provided for ensuring the separation of the blade from each of the plates during the opening of the latter so that both sides of each part may be readily reached for cleaning purposes.

The constructions are hereinafter more fully described and are illustrated in the accompanying drawing in which

Fig. 1 is a plan view of my razor;

Fig. 2 a longitudinal section thereof;

Fig. 3 a side elevation showing the razor opened;

Fig. 4 a plan view of Fig. 3;

Fig. 5 an enlarged detail in plan of the blade holder showing its hinged connection with the base plate and showing part of a blade;

Fig. 6 an enlarged sectional detail in the line 6—6 in Fig. 5;

Fig. 7 an enlarged sectional detail on the line 7—7 in Fig. 5;

Fig. 8 a plan view of a strip of material from which the blades are punched; and

Fig. 9 a cross section of the base plate showing the holder and blade therein in their positions when the razor is opened.

In the drawing like numerals of reference indicate corresponding parts in the different figures.

The razor comprises a handle 1 which is attached to a base plate 2 on which is hinged a cover plate 3. A blade 4 is carried by a holder 5 which is hingedly mounted on the pintle of the first mentioned hinge to lie between the plates 2 and 3. The double hinge connection comprises a pintle 6 carried by spaced lugs 2^a on the base plate 2. The holder 5 is provided with two bent up bearing flanges 5^a which are disposed on the pintle between the lugs 2^a, and the cover plate is provided with a hinge knuckle 3^a also disposed on the pintle between the bearing flanges 5^a.

Preferably the holder is made from sheet metal which is cut and stamped to the desired shape. To materially strengthen the holder adjacent the flanges 5^a I extend the metal between them beyond the ends thereof to form a tongue 5^c which is bent back on the body of the holder to lie between the said flanges.

To ensure the blade holder 5 and thus the blade 4 carried thereby being moved away from the base plate 2 when the razor is opened as shown in Figs. 3 and 6, I provide the hinge knuckle 3^a with a projection 3^b adapted to engage and swing the holder with it when the cover plate 3 has been swung a predetermined distance away from the base plate. The swinging movement of the holder 5 is limited by providing its flanges 5^a with projections 5^b adapted to engage a shoulder 2^b formed between the lugs 2^a on the base plate 2. From this description it is obvious that if the blade should adhere to the cover plate 3 while the latter is moving to its open position the projections 5^b will engage the shoulder 2^b to stop the swinging movement of the holder whereby the movement of the cover plate will continue until its projection 3^b engages the holder. If the blade should adhere to the base plate 2 while the cover plate is moving to its open position the projection 3^b will engage the holder, after the plate 3 has been moved a predetermined distance, to carry the holder along with the said plate until the projections 5^b engage the shoulder 2^b. Of course, the projections 5^b will be engaged by the shoulder 2^b to move the holder 5 away from the cover plate 3 if the base plate 2 be swung relative to the latter. Thus the blade 4 will be moved clear of both plates whichever plate is moved relative to the other.

To prevent the projections from being damaged if the plates are separated forcibly, I provide the hinge knuckle 3^a with a projection 3^c which is also adapted to engage the shoulder 2^b to limit the separation of the plates 2 and 3.

Referring to Fig. 8 it will be noted that one end of the blade is provided with a tang 4^b and the other end with a recess 4^c. The tang on one blade and the recess in the adjacent blade are simultaneously formed by punching a knockout portion 4^d in the strip. It will also be noted that the ends of one blade abut those of the adjacent blades which is accomplished by forming lines of weakness in the portion of the strip adjacent its edges and intermediate the transverse edges of the knockout portions. That is to say the knockout portions are formed between the lines of weakness and extend on opposite sides

thereof lengthwise of the strip. With this arrangement the knockout portions do not extend to the longitudinal edges of the strip which edges are thus continuous.

5 The tang 4^b is formed by recessing one end of the blade between each of its edges and the central portion thereof. Fingers 5^c formed on the holder 5 are bent over the blade engaging surface thereof to form a socket adapted to receive the tang. The end of the latter is provided with a notch 4^e adapted to engage an abutment such as the bearing flanges 5^a on the holder 5. The blade is normally held in the socket 5^c and against the abutment 5^a by lugs 5^e which are formed in any 10 suitable manner on the blade engaging surface of the holder for engagement with notches 4^f formed in the sides of the tang. In addition to these lugs 5^e, the holder may be provided with a raised projection 5^f for engagement with the 15 sides of an opening formed in the blade. From this description it follows that the blade may be removed from the holder by springing the blade to clear the projection 5^f and lugs 5^e and then by withdrawing it from the socket 5^c.

20 The other end of the blade is centered by contact points 7 carried by one of the plates 2 or 3 and adapted to be received in holes 7^a formed in the other plate. These points engage shoulders 4^g formed by the edges of the recess 4^c and the points are tapered to facilitate the engagement of the shoulders with the points. By providing another point 7^b intermediate the ends of the plates 2 or 3 for engagement with an opening in the blade, the latter is centered for engagement with the points 7. As the blade first engages the point 7^b a progressive registration of the points and blade is obtained during the closing movement of the razor.

25 The blade engaging face of the cover plate 3 is concaved transversely thereof and the adjacent face of the base plate 2 is correspondingly shaped to flex a blade clamped between the plates. The plates 2 and 3 are provided with grooves 2^c and a recess 3^e to provide clearance for the fingers 5^c and the body of the holder 5 respectively.

30 A latch 8 pivoted at 9 on the cover plate 3 is provided with a cam face 8^a adapted to be sprung into engagement with the underside of the base plate 1 to frictionally lock the parts in position for use. Referring to Figs. 2 and 4 it will be noted that the plates 2 and 3 are recessed to correspond to the recess 4^c in the blade which recesses are adapted to receive the latch 8 whereby it will not project beyond the end of the plates. The center of the pivot 9 is offset 35 inwardly relative to the inner edge of the recess in the base plate so that the distance between the corner of this edge of the recess and the center of the pivot is greater than the distance between the said center and the underside of the base plate on an imaginary line passing through the center at right angles to the underside. Therefore when the latch is sprung into its locking position any tendency of the latch to move 40 off the underside of the base plate will be resisted.

45 The handle 1 lies in a plane passing through the longitudinal center line of the base plate 2 and perpendicular to it but is inclined at an angle of more than 90° to the said center line away from that end of the base plate with which the latch 8 engages. To obtain the best results it has been found in practice that this angle should be 120° and therefore the cutting edges 50 of the blade lie at an angle of 60° to the center

line of the handle. Preferably the handle is connected to the base plate 2 at a point slightly closer to the hinged end thereof than to the latched end.

5 From this description it is obvious that the razor may be readily opened for cleansing purposes without removing any of the parts and may be readily closed for use without gathering up or handling the individual parts. By opening the clamping plates 2 and 3 and flexing the blade 10 intermediate its ends it may be released from the lugs 5^e and projection 5^f and thus be removed from its holder and a new blade inserted therein.

I provide each blade with a plurality of centrally located openings 4^g. In addition to this 15 row of centrally located openings 4^g I punch another row of openings 4^h between the first row and each edge of the blade and arrange the openings so that the distance between any two adjacent openings is substantially equal. This arrangement 20 prevents distortion of the blade during the hardening thereof and the rows of openings 4^h facilitate the flexing of the blade adjacent the edges thereof and the handling of the blade while it is being inserted in or removed from the 25 holder 5.

In Fig. 8 the punching operation has been completed to form a blade at the end of the strip of blade stock. It will be noted that the cut out portions on opposite sides of the tang 4^b and the 30 inwardly directed notches 4^e reduce the area of the blade stock at the base of the tang which permits the remainder of the blade to flex relative to the tang. Thus the flexibility of the blade adjacent its edges is not affected by the flexibility 35 of the holder 5 in which the tang is carried.

To ensure an even contact between the cover plate 3 and the blade throughout the length of the latter, the said plate is slightly convexed longitudinally thereof so that as the latch 8 is engaged with the base plate the plate will be straightened out to bring its ends into contact with the blade. Lugs 3^d formed at the corners of the plate 3 are adapted to overlie the corners of the blade 4 to prevent the latter from cutting or 45 scratching the face while it is being shaved.

The base plate 2 is formed of rolled stock which is channel or U-shaped at 2^d intermediate its guards 2^e. In other words this U-shaped portion extends lengthwise of the strip of metal and substantially centrally thereof as shown in Fig. 9 so that by cutting back from the guards to the vertical legs of the U and by cutting the horizontal leg of the U between the vertical legs thereof, the lugs 2^a and the shoulder 2^b may be readily 55 formed. During the rolling process the grooves 2^c at opposite sides of the channel 2^d are formed. This channel receives the contact pin 7^b, the riveted over end of the handle 1 which is riveted to the horizontal leg of the channel and also the 60 bearing flanges 5^a of the holder 5 to prevent lateral displacement of the hinged end thereof when the razor is closed (see Fig. 2).

65 While the guards 2^e are shown as being formed of a plurality of teeth any other well known type of guard may be employed.

What I claim as my invention is:

1. In a safety razor the combination of a base plate; a cover plate; a hinge connection between the said plates at right angles to the longitudinal center line thereof; a blade holder pivotally mounted on said hinge connection; means for moving the holder relative to the base plate when the cover plate is moved to open position; means for limiting the movement of the holder relative 75

to the base plate when the cover plate has moved a predetermined distance away from the base plate; and stop means carried by the cover and base plates for limiting the movement of one plate relative to the other plate.

5. 2. In a safety razor the combination of a base plate; a cover plate; a blade holder adapted to carry a double edged razor blade; a hinge pin carried by the base plate at right angles to the longitudinal center line thereof; and hinge knuckles carried by the cover plate and the blade holder pivotally mounted on said pin, the cover plate hinge knuckle having a projection for engaging the blade holder to move it away from the base plate when the cover plate has been swung a predetermined distance, and having a projection adapted to engage the base plate to limit the movement of the cover plate relative to the base plate.

10. 3. In a safety razor the combination of a base plate; a cover plate; a blade holder adapted to carry a double edged razor blade; a hinge pin carried by the base plate at right angles to the

longitudinal center line thereof; hinge knuckles carried by the cover plate and the blade holder pivotally mounted on said pin, the cover plate hinge knuckle having a projection for engaging a part of the base plate to limit the swinging movement of the blade holder relative to the base plate; and a projection carried by the cover plate for engagement with the base plate to limit the movement of one plate relative to the other plate.

15. 4. In a razor, a base plate formed with a channel shaped central portion and a guard extending from the top of the channel wall at each side, the side walls of the channel extending beyond the bottom of the channel and the guards at one end to form bearing lugs; and a blade holder having bearing flanges hinged on said lugs, the said flanges being adapted to be snugly received between the said side walls of the channel.

HOWARD ADDISON JOHNSTON.
